Atty.

UNITED STATES PATENT OFFICE.

WILLIAM F. CREMEAN, OF FRANKFORT, INDIANA.

BRAKE-BEAM HANGER.

1,298,901.

Specification of Letters Patent. Patented Apr. 1, 1919.

Application filed April 1, 1918. Serial No. 225,978.

To all whom it may concern:

Be it known that I, WILLIAM F. CREMEAN a citizen of the United States, residing at Frankfort, in the county of Clinton and 5 State of Indiana, have invented certain new and useful Improvements in Brake-Beam Hangers, of which the following is a specification.

My invention relates to a new and useful 10 improvement in brake beam hangers and particularly to a hanger wherein it will be impossible for the pin to become accidentally lost or work out of the hanger when the same is in service.

15 As is well known a good many derailments are caused by the pins working out of the brake hangers, permitting the brake beam to drop and the brake head and shoes to fall under the wheels.

20 An object of my invention therefore is to provide a special form of pin and hanger arms wherein it will be impossible for the pins to work out of the hanger arms while the same is in service.

25 Another object of my invention is to so construct the pins and hanger that both arms of the hanger are identical and may be made from the same mold when casted, it only being necessary to invert one arm with 30 relation to the other.

Still another object of my invention is to utilize two pins that are also identical, so that although four members make up the entire hanger which includes the pins and 35 hanger arms only two different parts are used, the other two being duplicates.

Referring now to the drawings forming a part hereof,

40 Figure 1 is a side elevation of my hanger applied to a standard brake head;

Fig. 2 is a front elevation of the hanger;

Fig. 3 is a front elevation of the hanger arm;

Fig. 4 is a vertical section of the same;

Fig. 5 is a detail view of the pin, and

Fig. 6 is an end view of the same.

Referring first to Fig. 1 there is shown an ordinary brake head 1, the head forming no part of the invention, and a section of the 50 brake beam 2. Also a bracket 3 is shown to which the upper part of the hanger, now to be explained, is secured.

Referring now to Figs. 2, 3 and 4, it will be seen that the hanger comprises two 55 hanger arms 4 and 5 and two pins 6 and 7.

These arms 4 and 5 are absolutely identi-

cal in construction but oppositely arranged and one inverted with respect to the other. The pins 6 and 7 are also both of the same construction but one is inserted through the 60 hanger arm 4, while the other is inserted through the hanger arm 5.

The hanger arm 4 or 5 is preferably a cast article and may be of malleable iron or steel, and is provided with a strengthening rib 8 65 extending practically throughout its length and widened out at both ends of the hanger arm to form the lugs or projections 9 and 10.

The lug or projection 9 is countersunk or cut out forming a square recess 11 for the 70 reception of the square head 12 of the pin 6, and the opening 13 registering with the recess 11 is circular for the reception of the shank of the pin. Therefore when the pin is inserted in the opening 13 the head 12 will 75 rest in the recess 11 and cannot turn in said opening.

The lower portion of the hanger arm is slightly different, a circular opening 14 being formed in the lug 10 but having a projection 15 extending across the lower portion of said opening, said portion 15 of course being integral with the hanger arm.

Referring now to the pin 6 it is seen that it consists of the head 12, and the shank 16, 85 the outer end of which is first slightly reduced as at 17, and then has the protruding lip 18, which is semi-circular, and the distance between the end of the shank 16 and the lip 18, or in other words the width 90 of the reduced portion 17, is such that the lip 18 may pass over the outer surface of the projection 15 when the pin is in its locked position.

The hanger is assembled as follows: First 95 the hanger arm 4 is held with the recessed portion 11 as forming the top end, and the pin 6 inserted so that the head 12 will fit within the square recess 11, making sure however that the lip 18 on the other end is 100 pointing directly upwardly as shown in Fig. 2, and the pin then passed through the bracket 3.

Another one of the arms is then taken and first turned end for end with respect 105 to the first one; it is then turned upwardly 90°, or at right angles to the arm 4, and the end of the pin 6 passed through the opening 14 and then turned downwardly occupying the position shown in Fig. 2, the 110 lip 18 contacting with the projection 15 and thereby holding the two arms together.

It is impossible for the pin to come out unless the arm 5 is first raised again to an angle of 90°.

To put the lower pin 7 in place it is first necessary that the lower ends of the hanger arms be pressed slightly together, which is made possible by having the diameters of the openings 13 and 14 slightly larger than the diameter of the pin 6. After these arms are forced inwardly at their lower ends, another pin 7 is inserted through the opening 13, in the arm 5, but not so far that the head will seat in the recess 11, as first it is necessary to turn the pin until the lip 18 will pass behind the projection 15 and then the arms again pulled apart, seating the head 12 in the square recess 11, and of course after the brake head is inserted into place the lower ends of the arms 4 and 5 can not possibly come together, thereby assuring a locked hanger wherein the pins can not possibly work out or be lost in service.

From the foregoing it will be seen that the hanger consists of but two arms, one the duplicate of the other and two pins of the same kind, making the hanger one that is relatively cheap to manufacture and one that is easily assembled. Also there is no danger of either pin dropping out to thereby drop the brake beam and heads.

Having thus described my invention, what I claim as new and desire to secure by Letters Patent is:

35. 1. A hanger arm provided with pin openings, means located on the arm adjacent one opening for restraining a pin against turning movement in the opening, and means located on the arm adjacent the other opening for restraining a pin against sliding movement in said opening.

40. 2. A brake beam hanger comprising two hanger arms, both of said arms being identical in form but one inverted with respect to the other when in their set position, openings provided near the opposite ends of said arms, one of said openings being partly obstructed, and means passing through the openings in said arms and locking with the obstructing portions.

45. 3. A brake beam hanger comprising two arms identical in form and one inverted with respect to the other when in their set position, openings near the upper and lower ends of said arms, a recessed portion registering with one of said openings and said recesses being angular in shape, the other opening in said arms having a projection across a portion of the face, and a pin provided with an angularly-shaped head adapted to fit within said recessed portions and the end of said pin provided with a lip to pass over the projections on the face of said openings.

50. 4. A brake beam hanger comprising two

hanger arms identical in form and arranged in an inverted position one with respect to the other, a pin provided with an offset portion and a lip thereon adapted to pass through openings formed in said arms, one of said hanger arms to be positioned at right angles to the other when one of the pins is first placed in position and then to be swung downwardly to lock the said arms in their set position, and a second pin adapted to be passed through openings formed in the lower ends of said arms to thereby retain the hanger in its set position.

5. A brake beam hanger comprising two hanger arms both of said arms being identical in form but one inverted with respect to the other, an opening formed near the upper and lower ends of said arms, a projection across one of said openings in each arm and a pin adapted to pass through the openings in the upper ends of said arms, one of said arms being first turned to an angular position and then swung downwardly to lock said arms with respect to each other, and a second pin adapted to pass through the lower openings in said arms when said arms are swung slightly toward each other and to lock the arms after said pin is revolved and the arms again swung outwardly.

6. A brake beam hanger comprising an arm provided near its upper end with a circular opening and an angular recessed portion registering with said opening, a circular opening near its lower end and a projection extending across the lower portion of said opening, a second arm similar to said first mentioned arm but in an inverted position with respect thereto, a pin having an enlarged head seated in said recessed opening in the first mentioned arm and a lip on the opposite end of said pin and adapted to pass behind the projection on the face of the opening on the second arm, and a second pin similar to the first mentioned pin and having its enlarged head seated in the recess in the second mentioned arm and the lip formed on the outer end of said pin extending over the projection formed across the opening on the first mentioned arm.

7. A brake beam hanger comprising two arms identical in form but oppositely arranged and means for passing through openings in the upper ends of said arms when one of said arms is in an angular position and to lock the upper ends of said arm when said arm is again swung downwardly, and means passing through the lower ends of said arms when the lower ends of said arms are swung inwardly and to lock said arms when the lower ends of said arms are again swung outwardly.

8. A brake beam hanger comprising in part a hanger arm having lugs formed near its opposite ends, the lug at the upper end

of said arm being recessed and then provided with a circular opening registering therewith and the lug formed at the lower end of said arm provided with an opening 5 and having a part of said opening reduced by a projection across the lower portion of the face of said opening.

9. A brake beam hanger comprising in part a hanger arm provided with a rib extending substantially from end to end there-

of and terminating in two circular projections, one of said projections having an angular recess formed therein and an opening registering with said recess, and the lower projection having formed therein an opening and a projection extending partly across the face of said opening. 15

In testimony whereof I affix my signature.

WILLIAM F. CREMEAN.
